UNITED STATES PATENT OFFICE.

FRANK HENNEBÖHLE, OF CHICAGO, ILLINOIS.

OIL BURNER.

Application filed September 23, 1924. Serial No. 739,378.

To all whom it may concern:

Be it known that I, FRANK HENNEBÖHLE, a citizen of the United States, residing at Chicago, in the county of Cook and State 5 of Illinois, have invented certain new and useful Improvements in Oil Burners, of which the following is a specification.

The invention relates to oil burners such as are adaptable for use as a substitute for 10 coal fires for heating purposes or the like and generally has for its object to provide a burner of the type stated which operates on the gravity principle, which is simple and inexpensive of construction, and effectively 15 operable for the purpose for which it is designed.

The invention seeks to provide an oil burner of the type stated which is particularly compact and simple of construction and 20 operation and adaptable for being readily mounted within the fire pot of a stove or furnace and secured to the grate thereof, regardless of the particular style of grate, and in which the desired preheating and directing 25 of the draft air for effecting a most efficient fuel combustion is effectively provided for, means also being provided for readily regulating the flow of the fuel oil and for ensuring against waste of oil by overflow 30 due to carelessness on the part of the operator or an unforeseen emergency.

With the above and other objects in view, the invention further resides in those novel 35 details of construction, combination and arrangement of parts, all of which will be first fully described in detail, then be specifically pointed out in the appended claims and illustrated in the accompanying drawings, in which:

40 Figure 1 is a vertical cross section of my improved burner per se, the section being taken on the line 1—1 on Figure 2, the association with the burner of an overflow actuated cutoff device being also diagrammatically shown, the manner of connection of that 45 device with the burner and the manner of mounting that device in a fire pot being also indicated in dotted lines.

Figure 2 is a plan view of the invention. 50 In the drawings, in which like numerals of reference indicate like parts in all of the figures, 1 represents the base portion of the burner which is provided with an upright peripheral flange 2 which may be hook bolted as at 3 to the particular grate structure 4 upon which the device is to be mounted. The

base 1 is provided with a depending flange 5 which is adapted to engage the grate so as to provide an air space therebetween, it being understood that when the device is bolted upon the grate the surrounding apertures of the grate between the device and the fire pot wall may be covered over with fire clay or otherwise to render impossible the induction of draft air in any other manner than 65 through the burner, see Figure 1.

A frusto-coniform throat 6 extends upwardly from the base 1 and merges with a cylindrical neck 7 which extends up into, but short of, the top of a crown cap 8 which is 70 held in spaced relation with the neck 7 by the webs 9 (four being shown).

The crown cap 8 is curved downwardly to surround the neck 7 and provide a restricted discharge throatway 10 therebetween. 75

It will be readily observed that the draft air passing up through the grate will pass upwardly through the frusto-conical throatway 6 and the neck 7 and be directed against the top of the crown cap 8 and deflect downwardly through the restricted throatway 10 against the outer surface of the said throatway 6.

The outer surface of the frusto-conical surface 6 is provided with a plurality (four being shown) of stepped or terraced annular oil grooves 11, the lowermost groove 11, should the same overflow for reasons later to be described, discharging into an annular 90 overflow channel 12 confined by the peripheral flange 2.

When the device is in operation, fuel oil is fed to the uppermost oil groove 11 through the supply pipe 13, a needle valve 14 serving to control the feed as desired. The hand wheel of the needle valve may be suitably marked as at 15 to cooperate with an indicating point in revealing the degree of opening of the valve. 95

When in operation, oil being fed to the uppermost groove 11 will gradually overflow into the succeeding oil grooves and to start the device the oil in these grooves is ignited in any manner common in the use of burners of the type stated. As the crown cap 8 becomes highly heated the draft air directed against the top thereof will be pre-heated and so directed against the thin oil films provided by the oil grooves overflow as to vary effectively act to vaporize the same and effect efficient combustion thereof 110

in a manner producing a heating flame of great efficiency.

It will also be apparent that by directing the neck 6 up high into the crown 8, the 5 same is in a position for being relatively cool, not being in actual contact with the flame, thus tending to prevent burning out of the said neck and of the crown cap 8 by excessive heating. It will also be observed 10 by reason of spacing the crown cap from the neck in the manner in which it is spaced, the webs not extending up into the crown sufficient to divide circulation but in a manner for permitting perfect circulation 15 within the top portion of the crown cap, means are provided for effectively preheating the draft air and directing it against the oil to be consumed in a manner providing for efficient combustion.

20 Should the oil being fed into the uppermost groove 11 continue to overflow the same and the successive oil grooves, by reason of carelessness of the operator in failing to ignite the same or because of the 25 flame being snuffed out by some emergency, the oil would collect in the annular overflow channel 12 and if no safety means were provided might occasion great waste of oil and flooding of the fire pot.

30 To insure the cutting off of the fuel supply in case of an emergency, I splice a safety cut-off valve 16 into the fuel supply pipe, which said valve may be of any type desirable, such as is provided with a cut- 35 off stem held to the valve opened position against the tendency of a spring or other agency to close the same. In the embodiment shown in the drawings, the valve stem is indicated at 17 and a lever 18 is mounted 40 to normally engage the stem and hold it, against the closing tendency, to the open position.

A toggle link 19 is pivoted to the lever 18 and is provided with an abutment set 45 screw 20 adapted to engage the side of the valve to limit the movement of the link toward the said valve. The link 19 is pivoted at 21 to a bell crank lever which includes the long arm 22 and a short arm 23. The 50 short arm 23 is pivoted at 24 to a bearing 25 projecting laterally from the valve. A suitable bearing 26 projecting laterally from the valve provides for the proper pivoting of the lever 18.

55 The other end of the long arm 22 of the bell crank lever is connected to a bail handle 27 which carries a trip bucket 28. An overflow discharge pipe 29 is connected to the base 1 in communication with the annular 60 overflow channel as at 30 and the said discharge pipe is so positioned as to discharge an overflow of fuel oil from the annular channel into the trip bucket.

When sufficient oil has collected in the 65 trip bucket to over-balance the toggle con-

nection 19—21—23, the lever 18 will be permitted to swing downwardly on its fixed pivot 24, under the tendency exerted against the valve stem 17, to thereby permit closing of that valve and the cutting off of further supply of oil.

From the foregoing description, taken in connection with the accompanying drawing, it is thought the novel details of construction, manner of operation and advantages 75 of my invention will be readily understood by those skilled in the art to which it relates.

What I claim is:

1. A device of the class described comprising a base, a frusto-coniform throat extending upward from the base, a cylindrical neck extending upwardly from the throat and forming a restricted air duct, a heating and expanding crown cap supported by the 80 neck and into which the neck discharges and having a flat top spaced above but in close relation to said neck and the edge thereof extended out and curved downwardly inwardly to provide an expanding 85 space much larger than the area of the neck and a restricted annular air discharge throatway surrounding the outer surface of the frusto-coniform throat in close relation thereto, and means for directing a thin film 90 of oil to the outer surface of the frusto-coniform throat.

2. A device of the class described comprising a base, a frusto-coniform throat extending upward from the base, and having a series of relatively shallow annularly stepped oil grooves in the outer surface thereof, a cylindrical neck extending upwardly from the throat and forming a restricted duct, a heating and expanding crown cap supported by the neck and into which the neck discharges and having a flat top spaced above but in close relation to said neck and the edge thereof extended out and curved downwardly inwardly to provide an expanding 100 space much larger than the area of the neck and a restricted annular air discharge throatway surrounding the outer surface of the frusto-coniform throat in close relation thereto, and terminating on a horizontal 105 plane with the juncture of the neck and the throat just above the uppermost oil groove, and means passing through the throat wall for directing a thin film of oil to the outer 110 throat surface by discharging into the uppermost oil groove.

3. A device of the class described comprising a base, a frusto-coniform throat extending upward from the base, and having a series of relatively shallow annularly stepped oil grooves in the outer surface thereof, a cylindrical neck extending upwardly from the throat and forming a restricted duct, a heating and expanding crown cap supported 115 by the neck and into which the neck dis- 120

- charges and having a flat top spaced above but in close relation to said neck and the edge thereof extended out and curved downwardly inwardly to provide an expanding space much larger than the area of the neck and a restricted air discharge throatway surrounding the outer surface of the frusto-coniform throat in close relation thereto, and terminating on a horizontal plane with the juncture of the neck and the throat just above the uppermost oil groove, means passing through the throat wall for directing a thin film of oil to the outer throat surface by discharging into the uppermost oil groove, the said restricted annular discharge throatway being of a diameter greater than the uppermost oil groove but less than the succeeding ones thereof.
4. A device of the class described comprising a base having an upwardly extending annular flange confining an oil overflow groove and a depending flange providing a large air space beneath the base, hook bolts for hooking over the annular flange and passing through the openings in a grate when the device is mounted in a fire pot for use, a frusto-coniform throat extending upward from the base, a cylindrical neck extending upwardly from the throat and forming a restricted duct, a heating and expanding crown cap supported by the neck and into which the neck discharges and having a flat top spaced above but in close relation to said neck and the edge thereof extended out and curved downwardly inwardly to provide an expanding space much larger than the area of the neck and a restricted annular air discharge throatway surrounding the outer surface of the frusto-coniform throat in close relation thereto, and terminating on a horizontal plane with the juncture of the neck and the throat just above the uppermost oil groove, means passing through the throat wall for directing a thin film of oil to the outer throat surface by discharging into the uppermost oil groove.
5. A device of the class described comprising a base having an upwardly extending annular flange confining an oil overflow groove and a depending flange providing a larger air space beneath the base, hook bolts for hooking over the annular flange and passing through the openings in a grate when the device is mounted in a fire pot for use, a frusto-coniform throat extending upward from the base, and having a series of relatively shallow annularly stepped oil grooves in the outer surface thereof, a cylindrical neck extending upwardly from the throat and forming a restricted air duct, a heating and expanding crown cap supported by the neck and into which the neck discharges and having a flat top spaced above but in close relation to said neck and the edge thereof extended out and curved downwardly inwardly to provide an expanding space much larger than the area of the neck and a restricted annular air discharge throatway surrounding the outer surface of the frusto-coniform throat in close relation thereto, and terminating on a horizontal plane with the juncture of the neck and the throat just above the uppermost oil groove, means passing through the throat wall for directing a thin film of oil to the outer throat surface by discharging into the uppermost oil groove.

FRANK HENNEBÖHLE.
